(57) **CLAIM**

I claim the ornamental design for a foot care device, as shown and described.

DESCRIPTION

FIG. 1 illustrates a top view of the present invention. FIG. 2 illustrates a bottom view of the present invention. FIG. 3 illustrates a frontal plan view of the present invention. FIG. 4 illustrates a rear plan view of the present invention. FIG. 5 illustrates a left plan view of the present invention. FIG. 6 illustrates a right plan view of the present invention. FIG. 7 illustrates an upper perspective view of the present invention; and, FIG. 8 illustrates a lower perspective view of the present invention.

The drawings set forth a unique design for a foot care device. The broken lines shown in the drawings represent portions of the foot care device and attachments that form no part of the claimed design. The dash-dot-dash lines serve as boundary lines to disclaim portions of the surface area so demarcated.
